[57] CLAIM

The ornamental design for an inflatable kite, as shown and described.

DESCRIPTION

FIG. 1 is a perspective view of an inflatable kite showing my new design;

FIG. 2 is a rear elevational view;

FIG. 3 is a side elevational view which is a mirror image of the opposite side;

FIG. 4 is a top plan view, which is a mirror image of the bottom plan view; and,

FIG. 5 is a front elevational view.

No claim is made to the structure in phantom which is present for environmental purposes only.
